UNITED STATES PATENT OFFICE.

CLAUDE ALBEMARLE BETTINGTON, OF LONDON, ENGLAND.

APPARATUS FOR PULVERIZING COAL AND OTHER MATERIALS.

1,074,040.

Specification of Letters Patent. Patented Sept. 23, 1913.

Application filed November 15, 1909. Serial No. 528,150.

To all whom it may concern:

Be it known that I, CLAUDE ALBEMARLE BETTINGTON, a subject of the King of Great Britain, residing at the Junior United Service Club, 11 and 12 Charles street, St. James', and of 14 Half Moon street, Piccadilly, in the county of London, England, have invented certain new and useful Improvements in and Relating to Apparatus for Pulverizing Coal and other Materials, of which the following is a specification.

This invention relates to apparatus for pulverizing coal and other materials and it has special reference to an apparatus for pulverizing coal for direct use in furnaces and the like in which the coal in lumps is fed to a chamber or chambers having therein a series of rapidly rotating beaters which comminute the said lumps, and at the same time mix the coal with air and deliver the mixture to the furnace.

The chief object of the present invention is to provide a pulverizing apparatus which is more efficient and economical in its action than is the case with such apparatus as has been previously proposed.

According to the present invention the pulverizing chamber is provided with an outlet for the mixture of pulverized material and air, which outlet is constructed so that it forms a curve in continuation of the internal circumferential surface of the chamber. The mixture of pulverized material and air is ejected from said outlet vertically upward into a chamber provided with a suitable baffle or baffles which cause the mixture to be deflected in a downward direction whereby the larger particles of material fall to the bottom of said chamber from which it is returned to the pulverizing chamber by suitable means. The material to be pulverized is delivered to the pulverizing chamber at that point where the beaters immediately commence to act upon it so that said action may take place over practically the whole of the effective internal periphery of the chamber.

In order that my said invention may be clearly understood and readily carried into effect, I will describe the same more fully with reference to the accompanying drawings, in which:

Figure 1 is a front elevation of the complete apparatus. Fig. 2 is a side view of the same. Fig. 3 is an elevation on a larger scale of the pulverizing apparatus, and Fig.

4 is a sectional elevation on the line A—B of Fig. 3. Figs. 5 and 6 are respectively a sectional end elevation and a side elevation of a modified constructional form of beaters.

A is a shaft suitably connected or geared with an electric motor B or other source of power and upon the said shaft a number of beater arms A' are mounted, preferably arranged in duplicate as shown in Fig. 3, to the outer ends of which steel beater plates a are suitably attached. The said arms and the plates a serve as beaters and fan blades and rotate within a chamber A² whose inner circumferential wall is preferably concentric for the greater part of its circumference with respect to the axis of rotation of the vanes. In the constructional form of beaters illustrated in Figs. 5 and 6, the beater plates a are held between two flat disks A'^x which are riveted or otherwise secured to the boss A^{2x}. The said beater plates a are secured to the disks A'^x by means of pins a^x which are in turn retained in position by means of pins a'^x arranged transversely to the pins a^x. If one of the beater plates a encounters a rigid obstruction it will swing back and allow the said plate to pass the obstruction, the beater plate being kept in its normal position during the working of the motor B by the action of centrifugal force.

If desired the beater plates a may be secured to the disks A'^x by means of bolts or the like. Holes a^{2x} may be formed in the said disks to allow communication between the two sides thereof. The boss A^{2x} is preferably fixed to the shaft A by means of a copper rivet or rivets a^o which shear if the load becomes too great. In this event to prevent lateral movement of the beaters, the point of a bolt a^{3x} engages in a groove a^{4x} in the shaft A. The said chamber has an opening a' through which a chute B² projects to deliver the coal in lumps to the said chamber from a worm conveyer B' or other suitable feeding device connected with the source of coal supply. Another opening a⁴, preferably on the opposite side, serves as the principal air inlet and is covered with a hood G², which is provided with an adjustable shutter a² serving as the air inlet regulator. The position of the point of entry of the coal is, as shown, preferably at a point just beyond its exit—that is when considered in relation to the path of the beat-

ers, and consequently of the coal and air—
around the inner circumference of the ma-
chine and such that the said coal falls upon
a lip α^3 of the casing and immediately meets
5 an ascending beater or vane thus producing
an impact which shatters the lump into
small particles. The material to be pulver-
ized is thus delivered at such point in the
casing where the beaters immediately com-
mence to act upon it. The particles re-
bound against the circumferential wall of
the casing A^2 which is preferably provided
with projections or teeth A^3 which assist in
the reduction of the coal to fine particles and
15 from which projections or teeth the coal re-
bounds, and again meets other rapidly ro-
tating beaters or vanes. The said lip α^3 is
preferably formed with a plain internal sur-
face to insure the coal being reduced in size
20 before it reaches the corrugated or toothed
part of the casing. The chamber A^2 is pro-
vided with an exhaust pipe C through which
the intimately mixed coal particles and air
are ejected by the centrifugal action pro-
25 duced by the beaters or vanes. The said
pipe C enters the chamber A^2 by means of
a channel C' which is integral with or suit-
ably attached to the said chamber and joins
30 the latter at its surface to form approxi-
mately an involute curve in continuation of
the internal circumferential surface of the
chamber, whereby a better result is obtained
from the centrifugal action produced by the
35 beaters and the velocity imparted thereby to
the coal dust by the beaters. The said curve
is such that a particle projected from one of
the rotating beaters, will pass easily into the
said channel C'. The said curve in the ex-
40 ample shown is an involute of the internal
circular surface of the chamber for a certain
distance, after which it is a circle concentric
with the said chamber.

The aforesaid exhaust pipe C conducts the
50 mixture of coal dust and air to a separating
chamber D, preferably to the lower end
thereof as shown in Figs. 1 and 2, the said
chamber being provided with a suitable baf-
fle D' by which the current of air and coal
55 dust is deflected. The said baffle may be in
the form of a cone, within which the exhaust
pipe C projects, the mixture being thus
given a downward movement which causes
the separating of the larger particles of coal
60 to be more effectively obtained.

The velocity of the air after issuing from
the baffle is reduced, and any particles of
coal which are not then sufficiently fine as to
be held in suspension fall to the lower part
of the said chamber D and pass through a
65 suitable pipe E and its reduced continuation
 E^2 leading therefrom preferably through
the aforesaid air inlet side of the
pulverizing chamber A^2 to the lip α^3 where
the further reduction of the particles to the
required degree of fineness is completed, the

said particles being drawn into the machine
by the current of air induced by the beaters
as aforesaid. The said pipe E is made suffi-
ciently large and is preferably provided
with an adjustable shutter E' or the like so
70 that in certain cases, for instance during low
rates of firing, where it is desirable that the
air or other gas should not fall below a
certain minimum weight per unit of time,
by regulating the said shutter a certain
75 amount of the conveying gas, in addition to
the "oversized" product is allowed to re-
turn to the suction side of the pulverizer,
which gas added to the fresh gas or air
drawn from an outside source, maintains a
80 sufficient current within the machine and
pipes to handle the "oversize" and the
fresh material coming in for treatment.
The separating chamber D is provided with
an exhaust pipe F through which a pre-
85 determined quantity of air and coal dust en-
tering the machine is conducted to the fur-
nace or the like.

In certain circumstances, where for exam-
ple thermal efficiency or uniform fineness are
90 not of primary importance the separating
chamber may be dispensed with and the
mixture of coal particles and air led directly
from the pulverizing chamber A^2 to the fur-
nace or the like; or screens may be substi-
95 tuted for the said separating chamber or a
centrifugal separator or other suitable de-
vice may be used.

When very wet coal or other material is to
be pulverized, as is often the case, which as
100 is well known renders pulverizing more diffi-
cult, it is advantageous to use heated air or
other hot gases, as a conveying agent. For
this purpose a pipe G is suitably connected
105 to the hood G^2 through which the heated air
or gases enter, the said pipe being provided
with a suitable shutter G' for regulating the
supply or hot flue gases may be drawn
110 through pipe G and cold air through the
opening in the hood G^2 controlled by the
shutter α^2 in any desired proportions.

The aforesaid apparatus has been de-
scribed with reference to the treatment of
coal, but it should be understood that I do
not limit myself to this particular applica-
115 tion, as obviously it could advantageously be
employed with any friable substance or mix-
ture of substances which it is desired to re-
duce to a fine powder; further it could be
used in a modified form for atomizing or
120 carbureting liquid fuels whether volatile or
otherwise. Similarly when the said sub-
stance or substances are adapted, after being
pulverized, to be used for purposes of com-
bustion or partial combustion or to undergo
125 heating or roasting, I may intimately mix
the same in the manner aforesaid with gases
that support combustion other than air or
with combustible gases vapors or liquids or
a mixture of some or all as may be desired. 130

When two or more machines are working in parallel with several exhaust pipes F in connection with one common pipe communicating with the furnace, and one pulverizer 5 is stopped, it is necessary to prevent the air and coal dust from the other pulverizers from blowing back through the stationary machine; for this purpose a shutter H is provided in the exhaust pipe F which will 10 automatically close on the pressure in the pipe F exceeding that in the chamber D and will open when the pressure in the separating chamber exceeds that in the pipe F. The said shutter is pivoted and is provided 15 with an arm carrying an adjustable weight for setting the shutter to open when a desired pressure is reached in the separating chamber. The aforesaid worm conveyer B' is driven by means of the engagement of a 20 projecting band b on a wheel b' mounted upon a shaft b'' which is suitably geared with the worm B' with a groove or grooves formed in the shaft A of the pulverizer. The diameters at the bottom of these grooves 25 vary so that the speed of the worm B' can be varied by axially displacing the said

wheel b' to let the band b engage with one or other of the said grooves, the gearing which connects the shaft b'' with the worm being such that the lowering and raising of 30 the wheel b' to engage with the various grooves, can take place.

What I claim and desire to secure by Letters Patent of the United States is:—

In a pulverizing apparatus, the combination of a casing having teeth formed on its internal periphery and provided with an extension forming approximately an involute curve and serving as an outlet, beaters rotating in the casing, a supply chute at one 35 side of the casing for the material to be pulverized, a substantially horizontal lip in said casing below said chute upon which the material falls, and a chute at the other side of the casing by which the coarse material is 40 returned to said lip.

In testimony whereof I affix my signature in presence of two witnesses.

CLAUDE ALBEMARLE BETTINGTON.
